SET OF GAME PIECES

Verne L. Sellers, Chicago, Ill.

Application November 18, 1952, Serial No. 22,330

Term of patent 7 years

(Cl. D34—5)

To all whom it may concern:

Be it known that I, Verne L. Sellers, a citizen of the United States of America, residing at Chicago, Cook County, Illinois, have invented a new, original, and ornamental Design for a Set of Game Pieces, of which the following is a specification, reference being had to the accompanying drawing, forming a part thereof.

In the drawing:

Fig. 1 is a side elevational view of a game piece called a "squad";

Fig. 2 is a plan view thereof;

Fig. 3 is a front elevational view of a game piece called a "two-squad" piece;

Fig. 4 is a plan view thereof;

Fig. 5 is a side elevational view of a game piece called a "three-squad" piece;

Fig. 6 is a plan view thereof;

Fig. 7 is a side elevational view of a game piece called an "artillery";

Fig. 8 is a plan view thereof;

Fig. 9 is a side elevational view of a game piece called a "tank";

Fig. 10 is a plan view thereof;

Fig. 11 is a front elevational view of a game piece called an "airplane";

Fig. 12 is a side elevational view thereof;

Fig. 13 is a front elevational view of a game piece called a "shield";

Fig. 14 is a side elevational view thereof;

Fig. 15 is a front elevational view of a game piece called a "general";

Fig. 16 is a side elevational view thereof;

Fig. 17 is a front elevational view of a game piece called an "atomic bomb"; and

Fig. 18 is a plan view thereof.

I claim:

The ornamental design for a set of game pieces, as shown.
